J. F. OYLER

HATBAND

Filed Dec. 21, 1923

BY

Thos. J. Donnelly
ATTORNEY.

INVENTOR.
James F. Oyler

UNITED STATES PATENT OFFICE.

JAMES F. OYLER, OF DETROIT, MICHIGAN.

HATBAND.

Application filed December 21, 1923. Serial No. 681,976.

My invention relates to a new and useful improvement in a hat band and has for its object the provision of a hat band so constructed and arranged as to prevent the staining of the fabric of the hat or the ribbon usually attached thereto by the perspiration of the wearer.

Another object of the invention is the provision on the interior of the hat, of an attachment piece of fabric which is attached to the hat and to which some material which is impervious to perspiration may be attached so as to efficiently shield the fabric of the hat from the perspiration.

Another object of the invention is the attachment to the fabric of the hat of an attachment piece of material, to which a material impervious to perspiration may be attached, the line of attachment of said attachment piece to the hat being out of alignment of the line of attachment of the impervious material to the attachment piece.

Another object of the invention is the provision in a hat of a strip of material which is impervious to perspiration attached to an attachment strip mounted within the hat, the means of attaching said impervious material being coated with moisture proof material, such as shellac.

Other objects will appear hereinafter.

The invention consists in the combination and arrangement of parts hereinafter described and claimed.

The invention will be best understood from a reference to the accompanying drawings which form a part of the specification and in which,

Fig. 1 is a vertical sectional view of the invention applied to one style of hat,

Fig. 2 is an enlarged sectional view of the invention applied,

Fig. 3 is a sectional view of a fragment of a hat showing the attachment piece mounted thereon.

The invention in its preferred form is applied to a hat 7 shown in the drawings with the conventional brim 8. Mounted upon the interior of the hat, adjacent that portion where the sweat band 13 of the hat is usually mounted is an attachment strip, preferably made from a narrow strip of tape, although any suitable material may be used for this purpose, so long as it is strong enough to carry the parts attached thereto and thick enough to permit their attach-

ment thereto. This strip is attached to the fabric of the hat by stitches 10 which extend through the hat fabric and through the strip. After the strip 9 is attached to the hat 7 by stitching the stitches may then be shellaced or covered with some other sort of waterproof coating. The hat band 13 and some waterproof material such as oiled silk 11 is then sewed or otherwise attached to the strip 9. Stitching the hat band and the oiled silk is the preferable method of attaching the same to the strip 9 and the stitches are then covered with shellac or some other water proof coating on the interior of the hat, to prevent moisture following the stitches through to the attaching strip 9. It will be noted that the line of stitches 12 which secure the hat band and the oiled silk to the strip 9 are not in alignment with the stitches 10 which secure the strip 9 to the hat. By arranging these stitches out of alignment with each other any moisture which might follow the stitches 12 will not be permitted to come into contact with the stitches 10, so that the moisture cannot by following the stitches reach the fabric of the hat. If the stitches were to be in alignment with each other, or to touch each other or be positioned close to each other the moisture from the head of the wearer would be conducted to the exterior of the hat where it would stain the same after mixing with the dust generally present on the exterior of a hat.

While I have illustrated and described the preferred form of structure I do not wish to limit myself to the precise details set forth, but desire to avail myself of such variations and modifications as come within the scope of the appended claims.

Having thus described my invention what I claim as new and desire to secure by Letters Patent is:

1. In combination with a hat, a fabric attaching member stitched to said hat on the interior thereof, adjacent one edge of said member; a waterproof strip doubled upon itself and positioned with one of its doubled over portions in an engaging relation at one edge to said fabric attaching member; a hat band positioned in engaging relation to the other doubled over portion of said strip, said hat band and said strip being stitched to said attaching member, the line of stitching of said hat band and said strip

to said member being out of alignment with the stitching of said attaching member to said hat.

2. In combination with a hat, an attaching member stitched adjacent one edge to said hat; a moisture proof strip doubled upon itself and positioned with one of its doubled over portions in engaging relation at one edge to said attaching member; a hat band positioned in engagement with the other doubled over portion of said strip, said

hat band and said strip being stitched to said attaching member; the doubled edge of said strip lying between said hat and said attaching member, the line of stitching of said hat band and said strip to said attaching member being spaced from and out of alignment with the line of stitching securing said attaching member to said hat. ¹⁵

In testimony whereof I have signed the foregoing.

JAMES F. OYLER.
